K. M. Maltby,
his Attorney

UNITED STATES PATENT OFFICE.

GEORGE B. MALTBY, OF CLEVELAND, OHIO.

TRACK CONSTRUCTION.

1,173,596.

Specification of Letters Patent. Patented Feb. 29, 1916.

Application filed October 5, 1915. Serial No. 54,132.

To all whom it may concern:

Be it known that I, GEORGE B. MALTBY, a citizen of the United States, resident of Cleveland, county of Cuyahoga, and State 5 of Ohio, have invented a new and useful Improvement in Track Constructions, of which the following is a specification, the principle of the invention being herein explained and the best mode in which I have 10 contemplated applying that principle, so as to distinguish it from other inventions.

My invention relates to track constructions, its object being to provide a rail which will be economical of manufacture and efficient in the performance of its function. 15

The said invention consists of means hereinafter fully described and particularly set forth in the claims.

The annexed drawing and the following 20 description, set forth in detail certain means embodying my invention, the disclosed means, however, constituting but one of various mechanical forms in which the principle of the invention may be employed.

In said annexed drawing:—Figure 1 represents a cross-sectional view of a track construction embodying part of my invention. Fig. 2 represents a cross-sectional view of a rail embodying another part of my invention. Fig. 3 represents a side elevation of a fragmentary portion of the track construction, partly in longitudinal section. Fig. 4 represents a cross-section of the parts illustrated in Fig. 3. Fig. 5 represents a view 35 similar to that of Fig. 3, showing a modified method of effecting a bond in the track construction embodying my invention. Fig. 6 represents a cross-section of the parts shown in Fig. 5.

My invention, as illustrated by Fig. 1, 40 comprises a track consisting of abutting rails 1, each comprising a tread portion 2, two lateral legs 3, 3, each leg formed with a laterally extending flange 4, thereby forming an interior space 5, open at the bottom. The 45 abutting ends of the rails rest upon a tie-plate 6, and within the space 5 and extending from one rail to the next, is a splice bar 7. The splice bars are provided with suitable apertures 8 registering with apertures 9 in the rails, through which bolts 10 are passed and secured by means of nuts, 11.

The splice bars are given sections similar and equal in area to the interior space

formed so that they completely fill such 55 space at the joint. The weakest part of the track is therefore supported and reinforced, as will be apparent. Furthermore the splice bars by being located within the interior of the rails do not become detached therefrom, 60 even when the nuts and bolts become loose, and remain in place as long as the bolts do not fall out of the holes. Even should all of the bolts be removed, the splice bars will 65 retain their position for a sufficient length 70 of time to enable the track to be repaired and in the meantime retain the abutting ends in their proper alinement. In addition, the U-shaped form of rail may be rolled with greater advantage than the forms heretofore used, as I have found that a maximum 75 of homogeneity of molecular structure is obtained when this form of rail is rolled.

I have found, however, that the simple U-shaped form of rail shown in Fig. 1 may 80 be modified as illustrated in Fig. 2, to advantage. In this modification, I have provided an interior depending web 12 which webs intersect the interior space formed by the abutting rails and thus abut at the ends 85 of the latter. These flanges divide the interior space into two portions and instead of employing a single splice bar, I use two splice bars, each fitting snugly the two parts of the interior space, as shown in Fig. 4. As 90 before, the two splice bars rest upon the tie-plate 6.

The employment of the web 12 increases the moment of inertia of the rail, as will be apparent to anyone skilled in the art and 95 adds this advantage to the advantages already indicated in connection with that form of construction illustrated by Fig. 1.

The structure last described may be further modified, as shown in Fig. 6, by making 100 the splice bars integral with the tie-plates.

When it is desired to bond the rails, the web 12, in the construction illustrated in Fig. 4, may be made sufficiently short to form a space 13 between the lower edge of 105 the webs and the tie-plate, wherein the bond may be located and suitably welded to such lower web edge.

In the form illustrated in Fig. 6, I have shown a modification of the device to conform with a change of location of the point of welding the bond. In this case the bond is welded to the top portion of the web and

one of the tie-plate sections is shortened to provide the necessary space for this purpose and for receiving the bond itself. In this instance, the web 12 may extend to the tie-plate, as shown.

Having fully described my invention, what I claim and desire to secure by Letters Patent is:—

1. As a new article of manufacture, a rail having a double U-section, and comprising an integral head or tread-portion, two lateral and substantially parallel side webs, the lower end of each such side web being formed with an integral laterally extending flange having a lower flat contact surface, together with a central integral and downwardly extending web portion.

2. The combination with two abutting rails forming an interior space, each rail provided with an interior web intersecting such space; of splice bars in said space upon

opposite sides of said web and secured to said rails.

3. The combination of two abutting rails forming an interior space, each formed with an interior web intersecting the latter; a tie-plate on which the abutting rail end portions are supported; splice bars within said space, upon opposite sides of said web and secured to said rails.

4. The combination of two abutting rails forming an interior space and with an interior web intersecting said space; a tie-plate on which the abutting rail end portions are supported; and splice bars in said space upon opposite sides of said web, said bars being integral with said tie-plate and secured to said rails.

Signed by me, this 22nd day of September, 1915.

GEORGE B. MALTBY.
